UNITED STATES PATENT OFFICE

2,527,180

ALL-WEATHER CRUTCH

George E. Evens, Needham, Mass.

Application June 23, 1949, Serial No. 100,818

2 Claims. (Cl. 135—53)

1

This invention relates to crutches and the object is to provide a simple and effective construction having alternatively usable ground-engaging elements, the construction being one capable of quick adjustment to change from one such element to the other and not subject to getting out of order.

To prevent slipping crutches are commonly provided with tips of rubber, frequently with fabric or other friction material exposed in the face thereof. Such a ground-engaging element is inadequate when ice and snow are encountered. Under such circumstances a spike or a calk would be desirable. However, the user would sooner or later enter a house wherein the use of such a calk would be inadmissible.

I am aware that it has been proposed to provide crutches with calks adjustable to operative position. Some such arrangements were heavy and clumsy and presented projecting parts likely to catch the clothing or external objects. Devices having movable parts or joints closely adjacent the ground-engaging end of the crutch would with use accumulate slush or snow thereon and freeze up so that it became difficult or impossible to manipulate them. In accordance with the present invention a construction is provided free of such disadvantages.

The invention will be well understood by reference to the following description of the illustrative embodiment thereof shown by way of example in the accompanying drawings wherein:

Fig. 1 is a face elevation of a crutch illustrative of the invention;

Fig. 2 is an edge elevation of the same;

Fig. 3 is a fragmentary face view on an enlarged scale, showing a preferred form of latch mechanism;

Fig. 4 is a view similar to Fig. 3, showing the latch released;

Fig. 5 is an elevation of the parts seen in Fig. 3, as viewed from the right; and

Fig. 6 is a section on the line 6—6 of Fig. 5.

Referring to the drawings, I there show a crutch having an arm rest 10 supported by two side members 12 which latter are spanned by the hand-grip 14. The side members 12 do not extend to the ground but their lower ends are disposed in spaced parallel relation and joined by a horizontal pivot 16 on which is pivoted centrally a reversible leg 18. The pivot 16 is a substantial distance above the ground, say at least ankle high, out of the way of ordinary accumulations of snow, slush and the like on the ground. About a foot from the ground would be a suitable and desirable position.

The leg 18 carries at one end a tip 20 of rubber or the like, and at the other end a calk or spike 22. It will be clear that the leg 18 may be swung from the position of Fig. 1 and through

2

the dotted line position in Fig. 2 through an angle of 180° to present the calk 22 at the extreme lower end of the crutch instead of the tip 20, suitable means such as those hereinafter described being provided for releasably locking the leg in either of these relatively reversed positions. The parallel portions of the side members 12 support the leg providing a relatively long bearing for the same as against twisting forces exerted in the plane of the paper, viewing Fig. 1, which occur in the normal use of the crutch.

The means herein shown for selectively securing leg 18 in either of its two positions comprises (see Figs. 3 through 6) a latch lever 24 pivotally mounted on one of the side members 12 in a position above the pivot 16, which lever in the horizontal position of Fig. 3, engages under one or the other of two hook-like members 26 respectively located on opposite faces of the leg at opposite sides of the pivot 16. Herein these members are received between forwardly projecting flanges 28 on the lever 24. The other end of the latch lever, at the right in Fig. 3, in its closed position engages behind a keeper 30 on the other side member 12, and is retained by a swinging detent 32 having a shoulder 34 engaging over the upper edge of the latch lever (see Fig. 3). A spring 40 tends to press the detent to the engaged position of Fig. 3, the motion being limited by stop 38. One end of the lever 24 may be bent outwardly to handle portion 24h. A releasing lever 42 is pivoted on this handle member for a rotational movement limited by the pin and slot connection 44, Fig. 5. This releasing lever normally rests in the position shown, with a portion extending downwardly below the handle portion 24h of the latch. When the handle member is grasped by the fingers the normally closing movement thereof rocks this member 42 clockwise, viewing Fig. 5, causing its cam-like edge to operate on the projection 46 on the side of the detent 32, and presses the detent back to release the latch lever which may then be swung upwardly by the grasping hand to the open position of Fig. 4, thereby releasing the leg 18 for reversal. The edge of the detent 32 above the shoulder 34 is provided with a sloping portion 48 (Figs. 5 and 6) engaged by the latch lever 24 when it is swung back from the open position of Fig. 4, so that the detent will be pressed back to spring forward again when the latch lever has passed.

The latching means as a whole is at a relatively high elevation, out of the way of snow, etc. on the ground. Its construction is simple. The lever 24 is long and provides a favorable leverage for releasing the same from the hook 26 if falling snow is accumulated therein. The anchoring of the two ends of the lever 24 when it is closed, at widely spaced points on the two side members 12, contributes strength, and the lever also effectively

maintains the leg in position against strains in a plane perpendicular to the paper, viewing Fig. 1. The leg 18 is easy to grasp and to turn when its reversal is desired.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A crutch comprising an arm rest and two side pieces, a leg pivoted centrally of its length between the two side pieces on a horizontal axis at least ankle high, the ends of the leg carrying respectively a friction tip and a calk, a latch bar pivoted to one side member above said axis for releasably engaging the leg to maintain it in vertical position, and a keeper for the latch bar on the other side member.

25

2. A crutch comprising an arm rest and two side pieces, a leg pivoted centrally of its length between the two side pieces on a horizontal axis at least ankle high, the ends of the leg carrying respectively a friction tip and a calk, a latch bar pivoted to one side member above said axis for releasably engaging the leg to maintain it in vertical position, a spring-pressed locking detent for the latch on the other side member, the free end of the latch comprising a handle portion and a part carried by the handle portion moved by the grasping action of the fingers when taking hold of the handle to free the detent from the latch.
